AIR DISTRIBUTION OUTLET

Walter W. Kennedy, Rockford, Ill., assignor to
Barber-Colman Company, Rockford, Ill., a corporation of Illinois

Application June 3, 1947, Serial No. 752,040

3 Claims. (Cl. 98-40)

1

This invention relates to an air distribution outlet having an inner portion adapted to be separated from an outer portion to permit cleaning of the outlet or adjustment of the parts thereof.

The primary object is to provide a novel hinge mounting which facilitates separation of the inner part of the outlet for cleaning or the like without the necessity of complete detachment of such inner part.

A more detailed object is to provide a hinge mounting which permits separation of the inner unit simply by loosening a pair of screw elements.

Another object is to duplicate the hinges so as to permit swinging of the inner part of the outlet to an out of the way position by releasing the connection to either set of hinges.

Other objects and advantages of the invention will become apparent from the following detailed description taken in connection with the accompanying drawings, in which

Figure 1 is a perspective view of an air distribution outlet embodying the novel features of the present invention.

Fig. 2 is a cross section with the inner part separated.

Fig. 3 is a fragmentary view of a portion of Fig. 2 with the inner part in normal position.

Fig. 4 is a fragmentary sectional view taken along the line 4-4 of Fig. 3.

Fig. 5 is a perspective view of a part of the hinge.

While the invention is applicable to various types of air distribution outlets, it is shown for purposes of illustration incorporated in an outlet of rectangular shape comprising an outer part 10 adapted to be connected to an air supply duct 11 and an inner part 12 normally disposed within the outer part and cooperating therewith to form one or more passages 13 through which air from the supply duct is delivered into a room. The outer part 10 comprises two laterally spaced walls 14 rigidly connected at opposite ends by walls 15 and cooperating therewith to form a rectangular neck adapted for connection to a flanged branch 16 of the air supply duct. The lower portions of the side wall flare outwardly and are curled at 17 for abutment of the top of the bend with the wall of the room into which the air is discharged from the outlet.

The inner part 12 of the outlet comprises flaring side walls 18 connected by end walls 19 and substantially paralleling the outer walls 14 to define the air passages 13. In this instance, a deflector plate 20 extends along the center of the bracket holes 29.

2

inner unit and cooperates with the walls 18 thereof to form the other air passages 13.

In accordance with the present invention, the inner part 12 is pivotally connected to the outer part 10 to swing downwardly away from the latter about either of two axes 21 and 22 extending along the outer edges of inner side walls 18. The hinges are formed by four L-shaped brackets 23 having flanges 24 lying against inwardly depressed portions 25 of the end walls 15 and pivotally connected to the latter by rivets 26, friction washers 27 serving to avoid looseness at the hinge joints. The rivets 26 are located above the plane of the open end of the unit so that right angular flanges 28 on the brackets 23 will engage the top of the walls 18 and locate the inner part 12 of the unit in proper relation (Figs. 1 and 3) with respect to the outer part 10. The flanges 28 are punched out to form holes 29 which are threaded to receive the ends of screws 30 projecting through larger holes 31 in the inner side walls 18 adjacent the ends thereof, with the heads of the screws accessible from the undersides of the walls 18. The screws are held permanently attached to the walls 18, this being accomplished in the present instance by split washers 32 contracted in grooves 33 beneath the heads of the screws on the side of the walls opposite the heads. Thus, the screws are journaled in the walls 18 with their threaded ends always projecting from the upper sides of the walls in positions to enter the holes 29 of the brackets.

Normally, all four of the screws are threaded into the corresponding brackets 23 and tightened so as to clamp the inner part 12 in the closed position shown in Figs. 1 and 3. When it is desired to separate the inner unit so as to gain access to the interior of the outer unit 10, it is only necessary to loose the two screws on either side of the inner unit until they are released from their brackets 23. Then, the inner unit is free to swing downwardly about the axis on the other side of the unit which then remains suspended from the other set of brackets as shown in Fig. 2. To thus gain access to the interior of the outer unit, it is unnecessary for the workman to remove any fastening elements or hold the inner unit as it is being separated.

The normal assembled relation of the parts may be restored simply by swinging the inner unit 12 reversely and upwardly against the bracket abutments and the turning the screws 30 whose threaded ends are thus automatically brought into engagement with the threads of the

If the screws on the other side of the inner unit are loosened and this side of the unit thus released, the inner unit will thus swing downwardly about the axis 22 and remain suspended from the other side of the unit. Thus, it is immaterial which pair of screws is released, and the workman may select those on whichever side will afford most convenient access to the interior of the outer unit.

I claim as my invention:

1. An air distribution outlet comprising a rectangular unit adapted for connection with an air supply duct and having laterally spaced elongated outer side walls and end walls rigidly connecting the ends of said side walls, an inner unit disposed between said outer walls and having laterally spaced sides substantially coextensive and coacting with the respective outer side walls to form elongated air discharge openings along opposite margins of said outer unit, a pair of right angular brackets hinged on each of said end walls near the outer margins thereof to swing in the planes parallel thereto, and a flange on each of said brackets forming an abutment for one of said sides of said inner unit and having a threaded aperture opening toward such side, a screw journaled on said side in a position to enter said aperture when the side is in abutment with the adjacent flange, the two brackets along either side wall of said outer unit constituting a hinge for said inner unit permitting downward swinging of the latter when the screws on the other side of the inner unit are withdrawn from their brackets.

2. An air distribution outlet comprising a rectangular unit adapted for connection with an air supply duct and having laterally spaced elongated outer side walls and end walls rigidly connecting the ends of said side walls, an inner unit disposed between said outer walls and having laterally spaced sides coextensive and coacting with the respective outer side walls to form elongated air discharge openings along opposite margins of said outer unit, four hinge members pivoted on said end walls near the four corners of said outer unit to swing about axes parallel to said openings, each of said members having a right angular flange engageable with said inner unit on the outer surfaces of the sides thereof to limit the inward swinging of the inner unit, each member also having a threaded aperture opening toward one of said sides of said inner unit, and screws permanently attached to the corners of said inner unit and journaled in the latter to enter the respective ones of said apertures where-

by to permit downward swinging of said inner unit by disconnection of the screws on either side thereof from their associated hinge members.

3. Apparatus of the character described having, in combination, an outer rectangular unit having downwardly flaring side walls and end walls spanning the unit at opposite ends, an inner generally rectangular unit disposed within said outer unit and having sides flaring downwardly and laterally spaced inwardly from the respective side walls of the outer unit, the ends of said inner unit being disposed adjacent the end walls of said outer unit, hinge elements attached to one side of said inner unit at opposite ends and on the upper surface thereof, each of said elements having an upstanding flange thereon lying adjacent and paralleling the adjacent end wall of said outer unit, axially aligned pins pivotally connecting said flanges and said end walls for swinging of said inner unit about an axis extending along the outer edge of one side wall of the unit, members mounted on said end walls above and at opposite ends of the outer margin of the other side of said inner unit and having inwardly projecting flanges thereon overlying the latter margin and forming stops for limiting the upward swinging of said inner unit about said axis, said last mentioned flanges having threaded holes therein opening downwardly toward the free margin of said inner unit, and screws extending upwardly through said free margin and threading into said holes to hold the margin detachably against said stops.
